UNITED STATES PATENT OFFICE.

EDWARD H. CLEMENT, OF WASHINGTON, DISTRICT OF COLUMBIA, ASSIGNEE TO
EDWARD F. COLLADAY, OF WASHINGTON, DISTRICT OF COLUMBIA.

RADIO RECEIVING INSTRUMENT FOR SYSTEMS OF BROADCAST DISTRIBUTION.

Application filed March 13, 1924. Serial No. 689,028.

My invention relates to systems of radio broadcast distribution, and has for its object the supply of current for all purposes to subscribers' stations from a central station 5 or stations. An ancillary object is to arrange radio telephone subscribers' stations so that they may be identified with telephone subscribers' lines, supplied with current for all purposes of radio receiving, 10 over said telephone lines and from the standard centralized batteries employed in modern telephone exchanges, without substantially changing any central office circuits or apparatus, and without disturbing the 15 functions of the same as telephone apparatus per se.

I attain my objects in the following manner: I provide a receiving set, which may have the usual or any suitable form of antenna or wave collector, with an input circuit coupled to the wave collector, an output circuit coupled to the wired circuit or telephone line leading to battery terminals; and I connect the elements of the detector in 20 parallel, in such manner as to differentiate between incoming battery current and outgoing modulated current at the substation terminals. In particular, I have discovered that the filament circuit of a detector tube 25 may be treated as a parallel branch of the plate circuit for feed purposes, provided differentiation is made as before stated.

In applying this invention to wired circuits as such, it is necessary to provide for 30 supervision and maintenance from central, and it is desirable to provide for metering the substation service at the central office, all as set forth in my prior copending application Serial No. 581,829, filed August 14, 40 1922, patented January 6, 1925, as No. 1,522,357, and reissued December 15, 1925, as No. 16,231. The matter of metering is not disclosed herein, and forms no part of the present invention, but it is pointed out 45 that the flow of current for filament supply in the line, being unmodulated battery current, of perceptible wattage, can conveniently be used for operating a central office meter, employing the energy that would otherwise be lost in choke coils and the like. For supervision, the plate circuit of the tube 50 at the substation is included as a part of the line circuit, and therefore the changes that take place at the subscriber's station, which 55 become audible to him in his receiving tele-

phone, are also distributed over the plate circuit and line and are detectable or may be made audible by suitable means to an operator or supervisor at some other point on the line than the subscriber's station. The 60 connection which I have actually employed for this purpose involves a bridged battery with choke coils in the bridge, and a bridged receiving telephone, with an audio condenser in the bridge. The choke coils prevent short 65 circuiting of the modulated pulsating current from the plate through the main battery, and the condenser keeps objectionable battery current out of the receiving telephone. I use no phone condenser as such 70 in the circuit, finding it unnecessary, and it will be understood that in adjusting resistances the apparatus provided is a maximum, to suit the shortest lines, the line resistance as such being disregarded. In commercial practice, instead of using variable 75 resistance, it is obvious that each line, having a known resistance, may be balanced once for all, by inserting the proper fixed resistance in the filament circuit at the substation. The battery connection I have mentioned is one form only. Another standard method of connecting a central battery is between the two halves of a split repeating 80 coil, and in such case the supervising telephone can be connected across the terminals of the secondary of said coil, the primary being in series with the battery in the line circuit leading to the subscriber's station 85 being supervised. Other arrangements will 90 suggest themselves, but these two are standard practice and in accord with the arrangement of practically all modern telephone exchange systems.

In testing out this circuit, the maximum 95 current flow, using a UV199 tube, was 45 milliamperes, at maximum efficiency. As this is less than the current required for energization of a standard common battery telephone, it obviously comes well within the 100 limits prescribed by good practice.

My invention is illustrated in the accompanying drawings, in which

Fig. 1 is a diagram showing subscriber's 105 radio receiving circuits, connected to a common source of current supply.

Fig. 2 is a similar diagram showing receiving telephones at the battery end of the supply circuit.

Fig. 3 is a diagram of a complete sub- 110

scriber's station and line extending to a central office equipped with standard jacks, plugs and cord circuits, and with a common centralized battery adapted to be connected 5 to subscribers' lines through said jacks, plugs and cord circuits.

Fig. 4 is a fragmentary diagram showing a dynamic receiver which may be substituted for the headphone receiver shown in 10 Fig. 3. The parts included within the dotted lines in this figure may be substituted for parts included within the dotted lines in Fig. 3 without other change.

Referring to the drawings in detail in 15 Fig. 1, 1 and 2 are the antenna and ground connections, respectively, containing an antenna tuning condenser 3 and coupling coil 4 connected in series relation with said antenna and ground. The upper and lower 20 terminals of the coil 4 are connected through conductors 5 and 6, respectively, to the input terminals of a detector tube 7, the output or plate circuit of said tube containing a source of current 8, audio receiving means 25 9, and a feed back coil 10 connected in series relation. The source of current 8 is at a 30 distance from the receiving set proper and connected therewith over a pair of line wires 11-12, and is of sufficient voltage to act as 35 the usual "B" battery, for example about 22 volts, the filament 13, of the detector tube, is connected across the terminals of the common source 8, by way of the line wires 11-12 and a branch circuit consisting of a 40 choke coil 14, variable resistance 15, variable resistance 16, filament 13, and conductor 17. The resistance 15 is made sufficient to limit the current supply to the amount required by the filament 13, which resistance, in the 45 present instance is a 400 ohm rheostat, the resistance 16 being the usual filament rheostat of approximately 30 ohms.

In operation, the line wires 11-12 are 50 connected to the terminals 18-19 of the receiving set and the high resistance rheostat 15 adjusted to bring the filament 13 to approximately the proper working temperature, finer adjustments being made through the smaller resistance 16. This applies current to the filament from the common battery 8 over the following path: Battery 8, line wire 11, choke coil 14, resistance 15, filament rheostat 16, filament 13, conductor 17, and back over line wire 12 to the battery. 55 Battery supplied to the plate circuit also from the common battery 8 by way of line wire 11, audio receiving device 9, feed back coil 10, plate of detector tube 7, filament 13, conductor 17, and back over line 60 wire 12 to the battery. The circuits being thus suitably energized for receiving, reception is had by adjustment of the condenser 3 and feed back coupling between coils 4 and 10, in the usual manner.

65 Referring to Fig. 2, the circuit arrange-

ment and apparatus elements are the same as those in Fig. 1 just described except that means are provided for listening at the location of the battery, which means comprises a suitable audio receiving device or 70 devices such as the telephones 20 and 21 connected by means of a plug and jack connection 22 across the line wires 11-12 through audio condenser 23, the battery 8 being connected with the line 11-12 75 through suitable audio choke coils 24 and 25 to prevent short-circuiting of the audio currents through the battery.

The operation of the circuit arrangement of Fig. 2 is identically the same as that described for Fig. 1 except that after the radio receiving set is connected on to the line for energization and tuned in for receiving, the additional audio receiving means 20 and 21 80 may be connected in at a point on the line 85 remote from the receiving set, as, for example, a point near the battery 8.

In Fig. 3, which shows the system applied as part of the standard common battery telephone exchange system, the radio receiving circuit is substantially the same as that of Fig. 1 except that the input circuit of the detector tube 7 is inductively coupled to the collecting or antenna circuit through primary and secondary coils 26 and 27, the 90 primary coil 66 being preferably variable and connected in series with an antenna condenser 30 between the aerial 28 and ground connection 29. The output or plate circuit of the detector tube 7 contains the 95 usual audio receiving means 9 and feed back coil 10 connected in series therein and, in addition, a plug 69 also included in series relation and arranged to engage with a jack 100 70 connected across the telephone line conductors 11-12 terminating in multiple jacks 71 and 72 at a telephone central office, indicated at the right of the vertical dotted lines. The circuit of the filament 13 of the 105 detector tube 7 is connected across the terminals of the plug 69 by way of choke coil 14, resistance 15, resistance 16, filament 13, and conductor 17. The subscriber's 110 telephone set 73 is permanently connected to the telephone line 11-12 at the terminal connections 74-75 in the usual manner except that radio choke coils 76-77 are connected in the leads 78-79 extending from the said terminals to the subscriber's telephone set. All the circuits and apparatus indicated to the left of the vertical dotted lines in the drawing are situated at the subscriber's substation.

At the central office connection is made with the subscriber's line 11-12 through the multiple jacks by means of a plug 80 constituting the answering terminals of an operator's cord circuit of a well known type connected to the common battery 8 through 125 repeating coils 81 and 82. Bridged across 130

the calling side 83—84 of the operator's cord circuit, through a listening key 85, is an operator's telephone receiver 86. For the purpose of applying busy test potential to 5 the test multiple 87 and operating the usual cut-off relays, not shown, the plugs of the operator's cord circuit are provided with the usual tests or sleeve contacts 88—89, the test contact 88 of the answering plug having, 10 in the present system, connection with a special tone test device 90 of any known or other suitable form operable to produce a characteristic tone in the listening set of an operator testing the line by connecting the 15 tip of plug with the ring of the jack of a line rendered busy by virtue of the connection of said tone test therewith.

The combined radio telephone and telephone system for Fig. 3, operates as follows:

20 The subscriber at substation A, desiring to use his radio telephone receiving set, may call the central station either by raising his telephone receiver R from the switch hook in the usual manner, asking for radio service, 25 at the same time inserting his radio plug 69 in the jack 70, or he may vibrate his switch-hook to indicate his desire without attempting to communicate orally with the operator. In either case the subscriber's line circuit 30 will be closed and the operator will be signalled in accordance with usual practice. The operator finding that he wants radio service either by his verbal expression of the fact through use of his substation telephone 35 or by the fact that the line lamp flashes inserts, (or causes to be inserted into one of the subscribers' multiple jacks such as 71, by another operator,) the plug 88 of a radio service cord circuit C. When the plug 88 40 is inserted in the jack 71, plate circuit of the subscriber's radio telephone receiving set is closed or completed through the telephone central office common battery 8 over the following path. From the plus side of 45 the battery 8 through repeating coil 81, plug 80, jack 71, line wire 11, jack 70, plug 69, subscriber's radio telephone 9, feed back coil 10, plate and filament of detector tube 7, conductor 17, sleeve contact of jack 69, 50 sleeve contact of plug 70, line conductor 12, sleeve contacts of jack and plug 71—80 and through repeating coil 82 back to battery 8. Current for the filament 13 of the subscriber's detector tube is also supplied from 55 the common battery 8 through the connections just described extending from the battery terminals to the terminals of the subscriber's radio plug 69, and thence by way of choke coil 14, resistances 15 and 16, 60 filament 13, and conductor 17 to the plug 69.

The subscriber's radio receiving set being now properly energized for operation it remains only for the subscriber to tune the set in the usual manner as by proper adjustment of the condenser 67, coupling coils

26—27 and feed back coil 10. If while the subscriber's line is in use for radio telephone service, another subscriber should desire a connection therewith, the operator in making the usual busy test by touching the ring contact of one of the subscriber's multiple jack with tip of her calling plug, will receive, instead of the usual busy signal, the characteristic tone test furnished by the tone test device 90 by virtue of the connection 70 thereof through the ring contacts of the plug 88 and jack 71 with the multiple test wire 87. Upon receiving this characteristic tone test the operator is apprised of the fact that the line is busy only for radio telephone 80 service and so proceeds to call the wanted subscriber and establish the connection in the usual way through known or suitable means not shown.

In order to usefully employ the resistance loss in the choke coil 14 and resistance 15, the apparatus circuit connection included in the dotted line rectangle of Fig. 3 may be replaced by that of Fig. 4 in which the choke coil 14 forms the magnet of a dynamic receiver 92 the movable or armature coil 93 of which takes the place of the telephone receivers 9. Where the coil 14 subserves this double function it may be wound to a resistance sufficiently high to furnish substantially 95 all the resistance needed in the filament circuit and thus usefully apply the power consumed in reducing the filament current to the amount required. In this case the resistance 15 may be made very small or 100 eliminated entirely. A further advantage of this latter arrangement is that any audio currents passing through the choke coil will act on the field to augment the movements of the armature of the receiver, it being understood of course that the windings are connected in the manner to add their effect to the field and not differentially connected. 105

I claim:

1. In a system of radio broadcast distribution, a subscriber's station and a central station and line wires interconnecting them, a telephone, and a radio telephone containing a tube detector at the subscriber's station, a common source at the central station 110 supplying operating current to both telephone and radio telephone at the subscriber's station over the said line wires, means at the substation to split the voltage of said common source impressed upon the radio-telephone terminals, so as to apply different voltages to the filament circuit and the plate circuit of the detector, together with an inductance coil inserted in the filament branch 115 adapted to permit the passage of battery 120 current but to prevent leakage of voice currents, the plate circuit being connected directly to line.

2. In a system of radio broadcast distribution, a main station, a substation, line 125

- wires interconnecting the two, a radio telephone at the substation including a tube detector, a source of current at the central station adapted to supply current over the line wires at a proper voltage for the plate circuit, a branch circuit including means to suitably reduce said voltage for the filament circuit, and a receiving telephone connected to said plate circuit, together with an inductance coil inserted in the filament branch adapted to permit the passage of battery current but to prevent leakage of voice currents, the plate circuit being connected directly to line.
15. 3. In a system of radio broadcast distribution, a main station, a substation, line wires interconnecting the two, a radio telephone at the substation including a tube detector, a source of current at the central station adapted to supply current over the line wires at a proper voltage for the plate circuit, a branch circuit including means to suitably reduce said voltage for the filament circuit, an inductance coil in said branch circuit to prevent leakage of voice currents therethrough and a receiving telephone connected to said plate circuit, together with a second receiving telephone at the central station adapted to be connected with the line wires and thereby with the plate circuit at the substation.
4. In a system of radio broadcast distribution, a main station, a substation, line wires interconnecting the two, a radio telephone at the substation including a tube detector, a source of current at the central station adapted to supply current over the line wires at a proper voltage for the plate circuit, a branch circuit including means to suitably reduce said voltage for the filament circuit, an inductance coil in said branch circuit to prevent leakage of voice currents therethrough and a receiving telephone connected to said plate circuit, together with a second receiving telephone at the central station adapted to be connected with the line wires and thereby with the plate circuit at the substation, said second receiving telephone and said source of current at the central station being connected in parallel.
5. In a system of radio broadcast distribution, a main station, a plurality of substations, means at the substations including tube detectors for receiving radio waves, individual wire circuits from the main station to the substations with a single centralized source of current supply for the substation receiving means, connected to said wire circuits in parallel and distributing current thereby to the several substations, with audio choke coils in the common bridge containing said source, each of said substation tube detectors having a tube and a filament circuit connected to receive current from its wire circuit in parallel, with means in said filament connection or branch to prevent the passage of voice current therethrough.
6. In a system of radio broadcast distribution, a central station and a substation and metallic circuit line wires interconnecting the same, a wave collector and a tube detector, having a grid circuit properly related to said wave collector, a filament circuit and a plate circuit in proper relation to the grid, a source of current supply at the central station, and parallel metallic circuit branches at the substation containing the filament and the plate of the detector, to distribute thereto current received over the line wires from the central office source, said filament current branch containing means to prevent the passage of voice currents therethrough, and the plate circuit finding a return to the filament through the line wires.
7. In a system of radio broadcast distribution, a central station and a substation and metallic circuit line wires interconnecting the same, a wave collector and a tube detector having a grid circuit properly related to said wave collector, a filament circuit and a plate circuit in proper relation to the grid, a source of current supply at the central station, and parallel metallic branches at the substation containing the filament and the plate of the detector, to distribute thereto current received over the line wires from the central office source, together with means in the filament current branch for choking out plate current, said plate current finding a return to the filament through the line wires.
8. In a system of radio broadcast distribution, a central station, a common battery thereat, a subscriber's station and metallic line wires connecting said subscriber's station with said central station and common battery, a radio telephone at the subscriber's station, a tube detector, comprising an input circuit connected to the grid and filament of said tube, a plate circuit connected to the plate and through the line wires and central battery to the filament, and an energizing circuit for the filament, said plate or output circuit, and said filament energizing circuit, being metallically connected in parallel to the metallic line conductors, a receiving telephone in the plate branch and an inductance device in the filament branch.
9. In a system of radio broadcast distribution, a central station, a common battery thereat, a subscriber's station and metallic line wires connecting said subscriber's station with said central station and said common battery, a radio telephone at the subscriber's station, a tube detector, comprising an input circuit connected to the grid and filament of said tube, a plate circuit connected to the plate and through the line wires and said common battery to the

filament, and an energizing circuit for the filament, said plate or output circuit, and said filament energizing circuit, being 5 metallically connected in parallel to the metallic line conductors, a receiving telephone in the plate branch, and a rheostat and an inductance coil in the filament branch to reduce the voltage of the current supply to the filament and to prevent leak-
age of voice currents therethrough.

10. In a system of radio broadcast distribution, a central station, a subscriber's station and metallic line wires interconnecting them, a radio telephone at the subscriber's station, comprising a tube detector, an input circuit connected to the grid and filament of said tube, a plate circuit connected to the plate and filament, and an energizing circuit for the filament, said 15 plate or output circuit, and said filament energizing circuit, being connected in parallel to the metallic line conductors, and a receiving telephone composed of two co-operating elements, one included in the plate 20 branch and the other in the filament branch.

11. In a system of radio broadcast distribution, a central station, a subscriber's station and metallic line wires interconnecting them, a radio telephone at the subscriber's station, comprising a tube detector, an input circuit connected to the grid and filament of said tube, a plate circuit connected to the plate and filament, and an energizing circuit for the filament, said plate 30 or output circuit, and said filament energizing circuit, being connected in parallel to the metallic line conductors, and a dynamic receiving telephone having its field windings included in the filament circuit and its 35 actuating windings included in the plate circuit.

12. In a system of radio broadcast distribution, a subscriber's radio telephone instrument comprising a detector tube having the usual filament grid and plate circuits, means for energizing said filament 45 circuits, input connections for said grid circuit, and output connections for the said plate circuit, together with a common source of unipotential current connected in parallel to one side of said filament through an inductance coil, and to said plate circuit directly, the return from the plate circuit to the other side of the filament being through said source of current.

13. In a system of radio broadcast distribution, a central station and subscribers' stations, and metallic circuit line wires interconnecting them, a telephone and a radio 50 telephone at a substation connected in parallel across the said metallic circuit, a filament circuit and a plate circuit in said radio telephone metallically connected in parallel across the radio telephone terminals with an inductance coil connected between one side

of the filament and the line, a common source of current supply at the central station, means for switching the same to the subscribers' stations through the line circuits, a receiving telephone in the substation radio 70 telephone, and an operator's telephone at the central station adapted to be switched into connection with an individual line while the source of current is connected thereto.

14. In a system of radio broadcast distribution, a central station and subscribers' stations and metallic line wires interconnecting them, a radio telephone receiver having an audion tube with both filament and plate 75 circuits metallically connected across the line and a telephone connected across the same pair of line wires, at a substation, radio choking means in the telephone bridge, audio choking means in the radio telephone bridge, and audio choking means between one side 80 of the filament and the corresponding line wire.

15. In a system of radio broadcast distribution, a central station and subscribers' stations and metallic line wires interconnecting them, a radio telephone having a plate and a filament circuit and a telephone connected across the same pair of line wires, at a substation, radio choking means in the telephone bridge, and audio choking means in the radio 90 telephone filament bridge, with means at the central station to interconnect the lines in pairs for telephonic conversation, and a common source also at the central station to supply current over the metallic circuit 95 line wires to the subscriber's station for all purposes.

16. In a system of radio broadcast distribution, a central and a subscriber's station and metallic circuit line wires interconnecting them, a radio telephone receiving instrument at the substation including a tube detector with filament and plate circuits metallically connected across the line terminals, means to prevent shunting of voice currents 105 from the plate circuit through the filament circuit, means at the central station for supplying current to the substation for all purposes, a telephone in the plate circuit at the substation and a telephone with means to 110 connect it with the said circuit at the central station, said telephones adapted to superimpose audio undulations upon said current supply in the plate circuit, whereby conversation between the central office and the substation may be carried on over said circuit, 115 including the metallic line wires.

17. In a system of radio broadcast distribution, a central station and a subscriber's station with line wires interconnecting them, a radio telephone at the substation having a high-wound magneto telephone in its plate circuit, connected to the line, and a second high-wound magneto telephone adapted to be connected to the line at the central station,

said high-wound magneto telephones acting both as transmitters and receivers over the metallic line circuit and through the high resistance of the plate circuit.

5 18. In a system of radio broadcast distribution, a tube detector receiving set having its plate circuit extended to a distant point, and a pair of high-wound magneto tele-

phones directly connected therein, one at the same station with the receiving set, and 10 the other at the distant point, together with a source of high potential for said plate circuit also directly connected thereto.

In testimony whereof I hereunto affix my signature.

EDWARD E. CLEMENT.
